Attorney

UNITED STATES PATENT OFFICE.

EDWARD J. SCHAEFER, OF HESPELER, ONTARIO, CANADA.

PHONOGRAPH-CABINET.

1,349,439.

Specification of Letters Patent. Patented Aug. 10, 1920.

Application filed December 2, 1916. Serial No. 134,719.

To all whom it may concern:

Be it known that I, EDWARD J. SCHAEFER, a subject of the King of Great Britain, and resident of Hespeler, in the county of Waterloo, Province of Ontario, and Dominion of Canada, have invented certain new and useful Improvements in Phonograph-Cabinets, of which the following is a specification.

5 The present invention relates to talking machines and has particular reference to new and useful amplifying means associated with said machines.

10 The object of the invention is to effect certain improvements in the construction of talking machines whereby a more faithful reproduction of the recorded sound is obtained. To this end the machine is so constructed that the reproduced sounds are sweeter, more mellow and to a greater extent 15 free of foreign sounds such as is the case with machines of the construction heretofore commonly employed.

20 Another object of my invention is to provide a device of the class described having a plurality of compartments, having the sound amplifying means in a compartment above one containing the sound producing device, thus permitting the sound to travel upwardly.

25 Another object of my invention is to provide a phonographic cabinet of the class described which is simple in construction, that may be manufactured at a small cost and to provide improved amplifying means.

30 Other objects and advantages to be derived from the use of my improved phonographic cabinet, will appear from the following detailed description and the claims, taken with an inspection of the accompanying drawing, in which:

Figure 1 is a front elevation of my improved cabinet; and

Fig. 2 is a side elevation thereof partly in section.

35 Referring more particularly to the drawing, wherein similar characters of reference designate like and corresponding parts throughout the various views, C designates the cabinet in its entirety having supporting legs therefor, a top section 1, sound amplifying means provided in the compartment 2 supported by means of a partition 3 separating the first mentioned compartment from the second compartment 4 containing 40 the sound producing device. The front end 45 of the second compartment 4 being provided

with a plurality of hingedly connected doors 5 permitting access being had to the sound producing device.

A turntable 6 is rotatably mounted in the 60 partition 7 separating the compartment 4 from a larger compartment forming a record receiver which may be also used for other purposes.

65 My sound amplifying device comprises a plurality of parallel diagonally arranged flat resonant boards 8 and 8' preferably made of pine. I do not desire to limit myself to this particular species of wood as other kinds may be used to advantage. I 70 provide a third diagonal board 9 substantially parallel to the board 8. A top section 10 and bottom section 11 are attached to the free ends of the diagonally arranged boards for a purpose hereinafter described. An end 75 section 12 provides a closure means on one end for the diagonally arranged boards in conjunction with the top section 10 providing a drum compartment D forming an amplifier in conjunction with the board 8'. 80 The baseboard 11 of my amplifying and transmitting means is provided with an opening therein registering with an opening in the partition 3 to receive the throat of a horn 13. The opening 16 is provided for 85 the resonant board 8 of the drum D to give a careful resonant and increasing volume of the tone as reproduced.

85 In use a record is placed on the turntable 6 which coacts with the stylus of the sound producer 14 to produce the desired sound which is transmitted by means of the horn 13, to the sound amplifier from where it escapes through openings 15 provided in the front of my cabinet. 90

95 From the above description taken in connection with the accompanying drawing, it is thought that a clear and comprehensive understanding of the construction, operation and advantages of my phonograph cabinet may be had, and while I have shown and described the amplifying means as embodying a specific structure, I desire that it be understood that such changes may be made in said structure as do not depart 100 from the spirit and scope of the invention as claimed.

105 Having thus fully described my invention, what I claim as new and desire to secure by Letters Patent, is:—

110 1. A phonograph cabinet having an open front, a plurality of walls therein and spaced

from each other to provide multiple chambers, the intermediate chambers being in communication with each other and one of the same opening through the open front of 5 said cabinet, one of the other chambers also opening through the open front of the cabinet, while the remaining chamber is closed.

2. A phonograph cabinet comprising a hollow body having an open front, intermediate and outer spaced walls in the hollow body to provide therein superposed chambers substantially coextensive with each 10 other, one of said chambers constituting a

main sound passage, another chamber constituting a resonance compartment, said intermediate wall having an opening establishing communication between the main passage and said resonance compartment, the main passage opening through the front opening in said body, and the remaining 20 chambers forming supplemental sound modifying spaces.

In testimony whereof, I affix my signature hereto.

EDWARD J. SCHAEFER.
